AUTOMOBILE DOOR LOCKING MECHANISM

George Tasman, Brooklyn, N. Y.

Application May 12, 1936, Serial No. 79,223

11 Claims. (Cl. 292—223)

This invention relates to door locking mechanism for automobiles and the like.

It is an object of this invention to provide an automobile door latch in which the handles may be set substantially flush with the sides of an automobile body and which nevertheless may be opened with a single movement of the hand.

It is a further object to provide a mechanism of the character described which will operate easily and efficiently and at the same time afford ample clearance for the glass of the door.

It is a further object to provide a device of the character described which may be readily installed and which will be securely held in place and which will be ornamental and which, nevertheless, will operate efficiently at all times.

The invention accordingly comprises the features of construction, combination of elements, and arrangements of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a longitudinal section through the mechanism along the line 1—1 of Figure 2.

Figure 2 is an elevation of the device as viewed from the side of the car.

Figure 3 is an elevation of the latch mechanism with the door locked but in position to be operated by the inside handle.

Figure 4 is a similar view operated by the inside handle.

Figure 5 is a view of the device unlocked, ready to be operated by the outside handle.

Figure 6 is a similar view after it has been operated by the inside handle.

Figure 7 is a detail section on the line 7—7 of Figure 5.

In the drawings the numeral 10 designates a pillar of the car body and the numeral 11 a door. 45 These two parts being adapted to meet along a surface having the usual stepped formation as shown at 12 to provide a tight joint.

In accordance with this invention, the latch mechanism is mounted upon the edge wall of the door 13, instead of upon the inner face as has heretofore been customary, and a bolt 14 is pivoted about a pivot screw 15 transverse to the edge wall 13 of the door.

The latch mechanism of this fastening device 55 may be carried upon a plate 16 which may be

either inset into the face of the edge wall 13 of the door or, as shown in the drawings, it may be attached to the inner face of this edge wall, being held to the edge wall by screws or rivets 17.

This mechanism comprises primarily a bell 5 crank lever 18 held pivotally to the plate 16 by the screw 15 and controlled by a spring 19 attached at one end to the plate 16 as shown at 30 and at the other to the lever 18, the tension of the spring 19 being such as to hold the lever 10 18 in counterclockwise position as seen in Figures 3, 4, 5, and 6, with the bolt down. The bell crank lever 18 has one arm 21 having a projection 22 extending outwardly of the door through an arcuate slot 23 in the plate 16 and beyond 15 the edge wall of the door and carrying at its outer end the bolt 14. The projection 22 has a notch 22a of a radial width equal to the slot 23 and less than the radial dimension of the bolt 14.

The bolt may be inserted through the slot 23 20 by turning it sideways until the plate 16 comes in line with the notch 22a behind the bolt and then bringing the lever 18 to normal position, thus causing the sides of the notch to engage the edges of the slot 23 to provide a bearing for 25 the bolt upon each side of the slot 23. In this way the bell crank lever is partly held in place by its engagement of the slot 23 and at the same time, any thrust occurring upon the bolt 14 during the opening or closing of the door is 30 taken by the edge of the slot 23 and is not communicated to the pivot 15. The lever 18 has an upwardly projecting arm 24 by which it may be operated by the outer handle and a downwardly projecting arm 25 by which it may be operated 35 by the inner handle of the door.

In general the outer and inner handles may have the same general characteristics comprising a surface plate 26 having a central recessed portion 27 surrounded by an inturned flange 28 40 adapted to bear against the outer face or the inner face, as the case may be, of the side plates of the door. At one end, this plate 26 is provided with a projection 29 carrying a vertical pivot 30 for a handle 31, this handle being of a 45 shape to be concealed or substantially concealed within the recess 28 of the plate 26. To hold the plate 26 in place it may be provided upon the inner side at the end opposite the projection 29 with an auxiliary bracket 32 adapted to extend upon the inner wide metal of the door, so that the metal of the door is embraced between the flange 28 and the bracket 32. The other side of the plate 26 is held in place by an engagement between the projection 29 and the door. 50 55

For the inside of the car there is provided upon the door a stud 33 for the plate 26 adapted to extend within a recess 34 in the projection 29 of the plate, and a small screw 35 fitting in from the edge 6 of the projection 29 engages the stud 33 to hold the plate 26 in place. The plate 26 intended for the exterior is held in place by a screw 36 extending into the projection 29 from the back through the metal of the door.

10 Each of the handles 31 is provided, intermediate its length with a pivot 37 for the door operating mechanism. In the case of the outer door, this pivot 37 connects to an arcuate link 38 connected by a screw 39 with the arm 24 of the lever 15 18. The link 38 being slotted along an arc, about the screw 15 as the center as shown at 39a to receive the screw 39, so that the link 38 cannot be moved without operating the bell crank lever 18, but the bell crank lever may be operated without 20 moving the link and handle. This link 38 has an extension 40 provided with a recess 41 and there is pivoted upon the plate a pin 42 having a bent end 43 adapted to be moved into and out of engagement with the recess 41 in the link 38, by 25 turning the pin 42. The pin 42 has upon its inside a handle 44 by which it may be operated, thus in one position of the handle 44 the projection 41 will prevent movement of the link 38 and hence prevent operation of the door handle upon the 30 outside of the car, but in the other position of the handle, the projection 43 is out of the pathway of the link and the handle may be operated without obstruction to open the door.

The internal handle has its pivot 37 connected 35 by a link 45 to a bent end 46 of an operating rod 47 which is pivotally held to the side plate of the car by plates 48. This rod 47 has its other extremity bent to form an operating finger 49 to engage the edge 50 of the arm 25 upon the 40 lever 18. Thus when the inside handle 31 is pulled, the rod 47 will be rotated and the finger 49, by engaging the arm 25, will rotate the lever 18 to raise the latch, the pivot 39 sliding in the slot 39a without moving the outer handle.

45 In accordance with this invention, the catch upon the door to receive the bolt may be provided with two steps arranged in a vertical plane transverse to the side of the door as shown at 51 and 52 so that as the door is closed, the bolt 14 will 50 ride up over the surface of the projection to hold the door in place.

Since certain changes may be made in the above construction and different embodiments of the invention could be made without departing 55 from the scope thereof, it is intended that all matter contained in the above description or shown in the accompanying drawings shall be interpreted as illustrative and not in a limiting sense.

60 It is also to be understood that the following claims are intended to cover all of the generic and specific features of the invention herein described, and all statements of the scope of the invention which, as a matter of language, might 65 be said to fall therebetween.

Having described my invention, what I claim as new and desire to secure by Letters Patent, is:

1. A latch adapted for use on an automobile 70 door having a movable glass therein, comprising in combination a plate having a recess therein adapted to be mounted on the face of said door, a door handle mounted within said recess and pivoted to said plate at one end of said handle 75 about an axis parallel to the face of the door, a

bolt pivoted on a second plate in alignment with the edge wall of said door about an axis transverse to the edge wall and a link connecting an intermediate portion of said handle to said bolt.

2. A latch adapted for use on an automobile 5 door having a movable glass therein, comprising in combination a plate having a recess therein adapted to be mounted on the face of said door, a door handle mounted within said recess and pivoted to said plate at one end of said handle 10 about an axis parallel to the face of the door, a bolt pivoted on a second plate in alignment with the edge wall of said door about an axis transverse to the edge wall, a slotted link connecting an intermediate portion of said handle to said 15 bolt and means for operating said bolt from the inside.

3. A latch adapted for use on an automobile door having a movable glass therein, comprising 20 in combination a plate having a recess therein adapted to be mounted on the face of said door, a door handle pivotally mounted within said recess and pivoted to said plate at one end of said handle about an axis parallel to the face of the door, a bolt pivoted on a second plate in alignment 25 with the edge wall of said door about an axis transverse to the edge wall, and a slotted link connecting an intermediate portion of said handle to said bolt, said link having a notch therein and a catch upon said second plate in 30 position to enter said notch to prevent said handle being moved to open said door and means to operate said bolt from the interior.

4. A latch for an automobile body having a 35 door thereon, comprising in combination a catch adapted to be mounted on said body adjacent to said door, a plate adapted to be mounted on the edge wall of said door opposite said catch, a bolt pivoted to said plate about an axis transverse to the plate, the pivot of said bolt being nearer the 40 outer face of the door than the body thereof and being positioned to engage said catch, a handle adapted to be pivoted to the door about a vertical axis at one end of the handle and connections between said handle and said bolt whereby a movement of the handle will rock the bolt about its 45 axis to free it from the catch.

5. A latch for an automobile body having a door thereon, comprising in combination a catch 50 adapted to be mounted on said body adjacent to said door, a plate adapted to be mounted on the edge wall of said door opposite said catch, a bolt pivoted to said plate about an axis transverse to the plate, the pivot of said bolt being nearer the outer face of the door than the body 55 thereof and being positioned to engage said catch, a handle adapted to be pivoted to the door about a vertical axis at one end of the handle and a link connecting an intermediate portion of said handle to said bolt whereby a movement of said 60 handle will rock said bolt about its axis to free it from said catch.

6. A latch for an automobile body having a door thereon, comprising in combination a catch 65 adapted to be mounted on said body adjacent to said door, a plate adapted to be mounted on the edge wall of said door opposite said catch, a bolt pivoted to said plate about an axis transverse to the plate, the pivot of said bolt being nearer the outer face of the door than the body thereof and 70 being positioned to engage said catch, a handle adapted to be pivoted to the door about a vertical axis at one end of the handle and a link connecting an intermediate portion of said handle to said bolt whereby a movement of said handle will 75

rock said bolt about its axis to free it from said catch, and a catching mechanism engaging said link to prevent movement thereof.

7. A latch for an automobile body having a door thereon, comprising in combination a catch adapted to be mounted on said body adjacent to said door, a plate adapted to be mounted on the edge of the door opposite the catch, a lever pivoted to the plate having a bolt thereon, said plate having an arcuate slot therethrough and said bolt extending through said slot in position to engage said catch, said lever lying parallel to said plate and closely adjacent to said plate, an outside handle and means lying closely parallel to said plate for connecting said plate to said outside handle, an inside handle and means lying close to the inside face of said door for connecting said inside handle to said lever, whereby said mechanism is all kept to the edges of said door and the center space is free to receive a window.

8. A latch for an automobile body having a door thereon, comprising in combination a catch adapted to be mounted on said body adjacent to said door, a plate adapted to be mounted on the edge of the door opposite the catch, a lever pivoted to said plate and having a bolt thereon, said plate having an arcuate slot therethrough and said bolt extending through said slot in position to engage said catch, said lever lying parallel to said plate and closely adjacent to said plate, an outside handle and means lying closely parallel to said plate for connecting said plate to said outside handle, an inside handle and means lying close to the inside face of said door for connecting said inside handle to said lever, whereby said mechanism is all kept to the edges of said door and the center space is free to receive a window, each of said connections containing a lost motion device to permit operation from either handle without moving the other.

9. A latch for an automobile body having a door thereon, comprising in combination a catch adapted to be mounted on said body adjacent to said door, a plate adapted to be mounted on the edge of the door opposite the catch, a lever

pivoted to the plate having a bolt thereon, said plate having an arcuate slot therethrough and said bolt extending through said slot in position to engage said catch, an inside handle and an outside handle and connections between each of said handles and said lever for moving the bolt about its axis to free it from the catch, said connection between said outside handle and said lever comprising a slotted link and a catch mechanism adapted to be mounted upon said door for engaging said link to prevent movement thereof.

10. A latch for an automobile body having a door thereon, comprising in combination a catch adapted to be mounted on said body adjacent to said door, a plate adapted to be mounted on the edge of the door opposite the catch, a lever pivoted to the plate having a bolt thereon, said plate having an arcuate slot therethrough and said bolt extending through said slot in position to engage said catch, an inside handle and an outside handle and connections between each of said handles and said lever for moving the bolt about its axis to free it from the catch, the connection between said inside handle and said lever comprising a horizontal rod adapted to be pivotally mounted upon the door and having one end thereof connected by a link to the inside handle and having an arm at the other end to contact said lever to operate the bolt.

11. A bolt mechanism comprising a plate adapted to be mounted upon the end wall of an automobile door, a lever pivoted to the plate on an axis transverse thereto, a bolt carried by said lever, there being a slot through said plate through which said bolt extends, said bolt being radially of greater dimension than the width of said slot and being provided with grooves to engage said slot and transversely of less thickness than the width of said slot whereby said bolt may be inserted in said slot when turned sideways and when brought to normal position will be held in place and supported by the engagement of the edges of said slot with said groove.

GEORGE TASMAN. 45
